US00D748146S

(12) **United States Design Patent**
Inose et al.

(10) **Patent No.:** **US D748,146 S**
(45) **Date of Patent:** **** Jan. 26, 2016**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Mikio Inose**, Cupertino, CA (US);
Marcel van Os, San Francisco, CA (US)

(73) Assignee: **Apple Inc.**, Cupertino, CA (US)

(**) Term: **14 Years**

(21) Appl. No.: **29/515,696**

(22) Filed: **Jan. 26, 2015**

Related U.S. Application Data

(63) Continuation of application No. 29/449,297, filed on Mar. 14, 2013, now Pat. No. Des. 722,607, which is a continuation of application No. 29/423,886, filed on Jun. 6, 2012, now Pat. No. Des. 712,421.

(57) **CLAIM**

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

The FIGURE is a front view of a display screen or portion thereof with graphical user interface showing our new design. The outermost dashed broken lines in the FIGURE show a display screen or portion thereof, and form no part of the claimed design.

The dot-dash broken lines in the FIGURE and the areas within the dot-dash broken lines show portions of the graphical user interface that form no part of the claimed design.

1 Claim, 1 Drawing Sheet
(1 of 1 Drawing Sheet(s) Filed in Color)
